United States Patent

Des. 240,718
Patented July 27, 1976

240,718

TIMEPIECE FACE OR SIMILAR ARTICLE

Helmut Herz, Forest Hills, N.Y., assignor to Westinghouse
Electric Corporation, Pittsburgh, Pa.

Filed Nov. 14, 1974, Ser. No. 523,942

Term of patent 14 years

Int. Cl. D10—07

U.S. Cl. D10—126

The figure is a front elevational view of a timepiece face or similar article showing my new design, the rear being flat, plain and unornamented, and the edges being of no appreciable thickness.

I claim:

The ornamental design for a timepiece face or similar article, as shown and described.
